UNITED STATES PATENT OFFICE.

JOHN M. EDMUNDS AND CHARLES E. WALLIN, OF SALT LAKE CITY,
UTAH TERRITORY.

STOCK-CAR.

SPECIFICATION forming part of Letters Patent No. 248,414, dated October 18, 1881.

Application filed August 12, 1881. (No model.)

To all whom it may concern:

Be it known that we, JOHN M. EDMUNDS and CHARLES E. WALLIN, of Salt Lake City, in the county of Salt Lake, Utah Territory, have invented a new and Improved Stock-Car, of which the following is a full, clear, and exact description.

The object of our invention is to provide a new and improved car for transporting live stock in such a manner that the health and quality of the same will not be impaired by transportation.

In the accompanying drawings, Figure 1 is a plan view of our improved stock-car, part of the roof being broken out. Fig. 2 is a cross-sectional elevation of the same on line *x x*, Fig. 1. Fig. 3 is a cross-sectional elevation of the same on the line *y y*, Fig. 1.

Similar letters of reference indicate corresponding parts.

The stock-car *A* is provided with a roller, *B*, at each end, which roller is mounted on a suitably-jounaled shaft, *C*, with squared ends *D*, for receiving a key or like instrument for rotating this roller. Strong belts or bands *E*, of leather or strong webbing, are attached to these rollers or drums *B*, and extend longitudinally through the car. These belts *E* pass over transverse bars *F*, about two and one-half or three feet from the floor of the car, and through a series of stirrups or hangers, *G*, suspended by means of rods *H* from the roof *J* of the car. The car is also provided with outwardly-swinging doors *K* at the bottom of the sides of the car, these doors being opened to remove the manure, bedding-straw, &c., from the car. The car is further provided with hay-racks *L*, which are pivoted to the sides of the car, are held in an inclined position by a brace, *M*, and can be folded against the sides of the car when not in use. The sliding doors *N* in the roof of the

car are opened, and the hay is passed through these openings into the racks. Water and feed troughs *O* are pivoted to the sides of the car and can be folded up against the same when not in use. The water is conducted into the troughs *O* through pipes from the water-receiving troughs *P* at the top of the car, into which troughs *P* the water is conducted from the watering-stations.

The operation is as follows: When the desired number of animals are in the car the rollers or drums *B* are rotated by means of a ratchet-lever or crank-keys, whereby the belts or bands *E* will be drawn taut directly under the bellies of the animals, which are thus partly supported by these belts and are considerably relieved. Weak animals cannot fall upon the floor and cannot be trodden down or trampled upon by the larger and stronger animals. The animals will not be fatigued and will arrive at the end of the journey in a much healthier and stronger condition than the animals transported in ordinary cars. The cattle can be fed very conveniently during the trip, and the manure can be removed from the car without requiring the animals to leave the same.

We are aware that it is not broadly new to use in a cattle-car chains or ropes suspended or wound upon a roll, or to use a hinged feed-trough; but

What we claim as new and of our invention is—

The bars *F*, extending across the car, and the suspended stirrups *G*, in combination with bands *E*, which pass over said bars and through said stirrups, as shown and described.

JOHN MARION EDMUNDS.

CHARLES EDWIN WALLIN.
